(57) CLAIM

The ornamental design for a display screen or portion thereof with animated graphical user interface, as shown and described.

DESCRIPTION

FIG. 1 is a first view of a display screen or portion thereof with animated graphical user interface showing a first image in a sequence;

FIG. 2 is a second view of the display screen or portion thereof showing a second image;

FIG. 3 is a third view of the display screen or portion thereof showing a third image;

FIG. 4 is a fourth view of the display screen or portion thereof showing a fourth image;

FIG. 5 is a fifth view of the display screen or portion thereof showing a fifth image;

FIG. 6 is a sixth view of the display screen or portion thereof showing a sixth image;

FIG. 7 is a seventh view of the display screen or portion thereof showing a seventh image; and,

FIG. 8 is an eighth view of the display screen or portion thereof showing an eighth image thereof.

The broken lines in the drawings are included for the purpose of illustrating the display screen and portions of the graphical user interface and form no part of the claimed design.

The appearance of the animated graphical user interface sequentially transitions between the images shown in FIGS. 1-8. The process or period in which one image transitions to another image forms no part of the claimed design.
